UNITED STATES PATENT OFFICE.

MARSHALL WILFRED HANKS, OF PITTSBURG, PENNSYLVANIA, ASSIGNOR
TO GEORGE WESTINGHOUSE, OF PITTSBURG, PENNSYLVANIA.

METHOD OF MAKING GLOWERS FOR ELECTRIC LAMPS.

SPECIFICATION forming part of Letters Patent No. 690,856, dated January 7, 1902.

Application filed June 7, 1900. Serial No. 19,382. (No specimens.)

To all whom it may concern:

Be it known that I, MARSHALL WILFRED HANKS, a citizen of the United States, residing at Pittsburg, in the county of Allegheny and State of Pennsylvania, have invented a new and useful Improvement in Methods of Making Glowes for Electric Lamps, of which the following is a specification.

My invention relates to the manufacture of electric-lamp glowes that are non-conductive when cold and conductive when hot; and it has for its object to provide certain improved methods in the manufacture and treatment of glowes which shall facilitate such manufacture and treatment and at the same time insure the production of glowes that are more nearly perfect in composition and form than those heretofore generally produced.

With these ends in view I have devised the improvements which will be hereinafter described.

Certain means for practicing my invention are illustrated in the accompanying drawings, in which—

Figure 1 is a diagrammatic view of a three-phase arc-furnace for treating glowes. Fig. 2 is a diagrammatic view of a two-carbon arc-furnace; and Fig. 3 is a view similar to Fig. 2, but illustrating the furnace operated from a constant-current circuit.

It has been my usual practice in the manufacture of glowes to utilize the arc formed between two carbon electrodes in order to form a bead on each end of the glower, in which is embedded one end of a platinum terminal wire, and since an alternating current is usually employed for this purpose it has usually been found necessary to manipulate the glower by hand in order to keep the melted bead exactly on the end of the blank, the arc being so unsteady as to have a tendency to move around to either one side or the other of the melted bead, and thus correspondingly move the bead to one side or the other. I have found that by employing three-phase currents and three carbon electrodes a steady arc may be secured, so that the glowes may be fed into the arc automatically

by a machine, if desired, and thus insure the production of glowes all of definite length and uniformity as to the symmetrical location of the beads on their ends. I have also found in the manufacture of glowes that the fumes generated by the carbon arc-furnace have condensed on the glowes, thus rendering the composition of the latter impure. These impurities have been found very injurious, and I have therefore devised means for preventing such deposits. It has been usual prior to my present invention to prevent the condensation of the fumes on the glower by blowing a jet of air on the arc from above the same; but this was found undesirable, for the reason that it disturbed the arc, so as to prevent the securing of satisfactory results in the formation of beads. In order to overcome the difficulties above stated, I place the open end of a tube beneath the arc and connect the other end of the tube with a suitable apparatus for producing suction therein, and thus draw down all fumes or other foreign matter introduced into the arc from the electrodes, and thus prevent deposits upon the glower. I find in practice that the use of this suction not only removes all impurities from the arc, but does it without disturbing or interfering with its operation in connection with the glower.

Referring now more particularly to the drawings, in Fig. 1 the carbon electrodes or pencils 1, 2, and 3 are supplied with three-phase currents from a source 4, which may be either a three-phase dynamo or the secondary of a transformer. Inasmuch as it is desirable to maintain a constant current in the arc-furnace, I include in each conductor between each pencil or electrode and the source of the current a steadyng resistance 5, switches 6 being also shown for disconnecting the furnace from the source of current. The resistance 5 may be adjustable, if desired, in order to vary the temperature of the arc produced between the electrodes 1, 2, and 3. The means for producing suction to remove the fumes is indicated as a pipe 7, the open end of which is located adjacent to and beneath the ends of the electrodes between

which the arcs are formed. A blank 8, from which a glower is formed, is shown as supported by means of a pair of tweezers 9, so that its lower end is located in the arc for the purpose of forming a terminal bead thereon.

5. In Fig. 2 I have shown the two carbon electrodes 10 and 11 as supplied with energy from a constant-potential circuit 12, the steadyng resistances 13 being employed for the purpose of maintaining a substantially constant current. The apparatus here shown is also employed for the purpose of forming a bead on the end of the blank, the suction device 7 being used for the same purpose as in the apparatus shown in Fig. 1. In Fig. 3 the arrangement is the same as that shown in Fig. 2, except that the circuit 14 for supplying the current to the electrodes 10 and 11 is a constant-current circuit, and consequently the steadyng resistances 13 are not employed. In this figure a resistance 15 is shown as connected in shunt to the arc.

In each of the forms of apparatus illustrated it is of course possible to vary the amount of resistance in circuit, and though no specific means has been shown for this purpose the feasibility of adjusting or varying the amount of resistance in a circuit is so well known in the art that illustration thereof 25 has been deemed unnecessary.

I do not desire to limit my invention to any specific apparatus or to all the steps hereinbefore described. My invention is therefore not to be considered as restricted, except in 30 so far as limitations may be definitely expressed in the claims.

I claim as my invention—

1. The improvement in the art of treating glowers which consists in subjecting a glower-blank to an electric arc formed between a plurality of carbon electrodes and at the same time withdrawing the products of combustion by suction.

2. The improvement in the art of making glowers which consists in forming a terminal bead on the end of a glower-blank in an electric arc formed between a plurality of carbon electrodes and at the same time withdrawing the products of combustion by suction.

3. The improvement in the art of making glowers which consists in subjecting the glower-blank or some part of it to an arc formed between three electrodes supplied with current from a three-phase circuit.

4. The improvement in the art of making glowers which consists in forming a terminal bead on the end of the glower in an electric arc formed between three carbon electrodes traversed by three-phase currents.

5. The improvement in the art of making glowers which consists in forming a terminal bead on the end of a glower in an electric arc formed between three carbon electrodes traversed by three-phase currents and at the same time withdrawing the products of combustion by suction.

In testimony whereof I have hereunto subscribed my name this 4th day of June, 1900.

MARSHALL WILFRED HANKS.
